UNITED STATES PATENT OFFICE.

ALEXANDER LÉNART, JR., OF BUDAPEST, AUSTRIA-HUNGARY.

EXTRACTING METALS BY ELECTROLYTIC MEANS FROM ORES.

No. 826,485.

Specification of Letters Patent.

Patented July 17, 1906.

Application filed August 18, 1905. Serial No. 274,721.

To all whom it may concern:

Be it known that I, ALEXANDER LÉNART, Jr., engineer, a subject of the Emperor of Austria-Hungary, residing at Budapest, in 5 the Empire of Austria-Hungary, have invented certain new and useful Improvements in Extracting Metals by Electrolytic Means from Ores and other Metalliferous Substances; and I do hereby declare the following to be a full, clear, and exact description of the invention, such as will enable others skilled in the art to which it appertains to make and use the same.

My invention relates to a process and apparatus for extracting metals by means of acid radicals which are evolved in the electrolysis of alkali salts, more particularly of alkali chlorids; the electrolyte at the cathode being separated by a diaphragm from the 15 other fluid in order to allow of the products of the electrolysis which collect at the cathode being removed separately.

This improved apparatus differs from those in general use in that the current is not 20 passed through the material to be extracted, but that the chamber in which the electrolysis is carried out is arranged beneath the chamber which serves for the extraction and is separated therefrom by a permeable floor, 25 so that the cathodes and anodes may be arranged in direct proximity to one another. In the electrolyzing-chamber, therefore, merely a decomposition of the electrolyte takes place in the sense that the cations— 30 that is, the alkali—formed inside the diaphragms are withdrawn from the bath, while the anions—that is to say, the acid radicals—are carried upward into the extraction-chamber by the flowing anode fluid and dis- 35 solve the metal while traversing the layers of the material to be extracted. The electrodes, 40 which are uniformly distributed in large numbers under the floor carrying the layers of ore, are arranged in such a way that they 45 do not impede the upward flow of the electrolyte.

In the process it is of particular importance that the flowing electrolyte should first 50 pass over the anodes and only afterward over the diaphragms containing the cathodes, so that the electrolyte is already so far saturated with the acid anions before reaching the diaphragms that the lye diffused through the latter cannot precipitate the metals as 55 hydrate or oxychlorid from the electrolyte, which during the preceding circulation

through the extraction apparatus has absorbed metallic salts.

The advantages of this apparatus consist in the resistance of the cells being greatly 60 reduced, as the electrodes may be arranged in direct proximity to one another and the current has not to pass through the layers of ore, in the anions evolved being utilized as 65 fully as possible, because on the one hand the electric resistance of the layers of ore does not come in question, and thus the thickness of the layers may be increased according to requirements, and, on the other hand, any unconsumed chlorin can freely escape and be 70 further utilized—for instance, for producing chlorid of lime, hydrochloric acid, or the like. The formation of basic metallic deposits in the 75 cells is also avoided, and, finally, by the separation of the extraction-chamber from the electrolyzing-chamber the introduction of the material and the removal of the residuals may be effected without the slightest interruption of the electrolyzing apparatus, and damage to the electrodes and diaphragms by the ore is 80 entirely avoided.

The apparatus will be described in connection with the accompanying drawings, in which—

Figure 1 is a vertical section of the apparatus; Fig. 2, an end view; Fig. 3, a side view, on a reduced scale, from the side at which the cathode fluid is introduced; and Fig. 4, a side view, on a reduced scale, from the side at which the alkali hydrate formed is discharged. Fig. 5 is a horizontal section, on a reduced scale, on the line A B of Fig. 1. Fig. 6 is a detail showing a section, on larger scale, of the head-piece of a diaphragm-tube.

The trough serving for the electrolysis is 95 made of impermeable and acid-resisting material—for instance, beton, or wood, masonry, or the like, impregnated with asphaltum and the like. In the form of construction shown the floor C consists of beton 100 and the sides D of brick masonry with iron ties passed through the masonry, which form above and below, with frames of iron or wood, a solid scaffolding or skeleton for the masonry in order to increase the resistance 105 to lateral pressure of the thin walls. In accordance with the invention the trough is divided into an upper and under chamber by means of a false bottom E, provided with holes a, and preferably horizontal and 110 formed in the drawings as a vault.

The chamber F under the perforated bot-

tom E forms the electrolyzing or decomposing chamber, while the upper chamber H is the extracting or dissolving chamber into which the material (not shown) to be extracted is charged.

Preferably tubular diaphragms d of alkali-resisting material—such, for instance, as cement, asbestos, parchment, or nitrated cotton fabric—are arranged either horizontally or obliquely in the decomposing-chamber F. Within the diaphragm-tubes the cathode-chambers are formed, which contain the cathodes hereinafter described.

The diaphragm-tubes at the ends, which contain the connections for the cathodes, are carried separately through the walls of the trough or pan and tightly packed by means of suitable head-pieces g, which project to the outside and are separately connected with the alkali-hydrate collector I by means of connection pipes or pieces m, with the object that each diaphragm-tube may be separately watched and changed in case of need. The other ends of the diaphragm-tubes are connected by means of T-shaped tubes f in groups in order to diminish the discharge places in the walls. It would not, however, be of advantage to feed all the diaphragm-tubes through a common feed-tube f, as it is essential that the flow of the fluid through all the cathode-chambers should take place as uniformly as possible. Both the feed-tubes f and the head-pieces g must be made of alkali-resisting material, preferably earthenware. The diaphragm-tubes are when being constructed first cemented into the head-pieces g, then inserted in the pan, after which the lower ends, which are accessible through a manhole K, are connected with the feed-tubes and cemented in.

In the decomposing-chamber F there are suitably-shaped anodes b of insoluble material—for instance, graphite or carbon—arranged above or between the diaphragms, but in no case over the diaphragms, to which anodes the current is conveyed by means of feed-conductors c, made of the same material and carried tightly packed through the wall of the apparatus.

In Fig. 5 the first eight diaphragm-tubes from the left-hand side are shown, which are combined by means of a feed-tube f into a group, and adjoining them are, in this instance, twelve anode-plates. The anodes arranged under the diaphragm-tubes in the first group and the diaphragms arranged over the anodes shown are omitted for the sake of clearness. The importance of this arrangement for the process consists in that if, for instance, copper be dissolved by means of chlorin the anode electrolyte while flowing from below upward encounters first the anodes, absorbing from these so much chlorin that while it passes in front of the diaphragms, through which always some alkali

is diffused, neither copper oxychlorid nor copper hydrate can be precipitated from the already cupreous electrolyte. The cathodes h, which are preferably formed of nickel or iron wire or strips, are arranged in the diaphragm-tubes. Pieces of metal, preferably copper bars j, tightly packed in the branch mouths i of the caps g, serve for conveying the current and are connected with the collecting-bar M. The dissolving-chamber G of the apparatus is filled with ore H, which is to be treated, which rests on the perforated floor E. In the upper part of the dissolving-chamber pipes l are arranged, which serve for carrying off the metallic-salt solution obtained. Tubular nozzles L, opening into the lower part of the dissolving-chamber, serve for sluicing out the residuals.

Fig. 1 shows a cover N, the edges of which dip into the fluid close to the walls of the trough, and thereby form a gas-tight joint. The cover may be lifted or raised by means of chains and pulleys or the like and serves for collecting and carrying off the unconsumed gaseous acid radicals—for instance, chlorin gas. The perforated floor E is coated with a permeable acid-resisting filtering layer—for instance, asbestos cloth—in order to prevent the ore dust falling through into the electrolyzing-chamber or the stoppage of the holes of the false bottom E.

Fig. 6 shows the head-piece of the diaphragm-tubes on a larger scale. The arrangement of these head-pieces allows the diaphragm-tubes to fit tightly into the aperture of the wall of the trough and to remove said tubes readily; further, to change, if necessary, easily the cathodes. The head-piece g is fitted with india-rubber washers c', insuring a water-tight closure between the head-piece and the aperture of the wall of the trough. The head-piece is further provided with a shouldered recess g', in which the diaphragm-tubes are fitted by means of any suitable stuffing material. On the free end the head-piece is widened at g² and is formed with a lateral tubular projection e², through which passes a bolt i', preferably of copper, bearing on its inner end the connection-piece j', preferably of iron or nickel, projecting out of the mouth of the head-piece. The cathode is fastened in any suitable way—for example, by means of screws and soldering—to that projecting end of the connection-piece j'. Washers k' and a nut q' serve for tightening the bolt i' in the opening e². However, the bolt i' may be tightened in any suitable manner. The flange f' serves to connect the head-pieces to the tubes leading to the alkali vessel.

The working of the apparatus is as follows: The anode fluid, which at the commencement of the operation consists of an alkali-salt solution, but afterward of a mixture of this salt solution with the metallic-salt solu-

tion to be formed, passes through pipes *k*, (see also Fig. 5,) made of acid-resisting material, under the anodes in the decomposing chamber *F*. While the electrolyte flowing upward passes over the anodes, it absorbs the produced acid radical—for instance, chlorin—and carries this with it over the apertures *A* of the separating-floor *E* into the dissolving-chamber *G*, saturates the layer of ore *H* uniformly, dissolves its metallic contents, and leaves the apparatus through the pipes *l*, after which the solution, according to the circumstances of working, is either immediately freed from metals and from here passes back into the electrolyzing-chamber of the apparatus or the electrolyte is passed several times through the extracting apparatus *g* before being freed from metals until the desired salts contents is reached. The alkali salt solution forming the cathode fluid passes through the feed-pipes *f* into the cathode-chamber *e*—that is to say, into the diaphragm-tubes in which the alkali metal is separated out on the cathodes *h*, which metal, as is well known, immediately forms with water alkali hydrate. The mixture of the alkali salt and alkali-hydrate solution thereby resulting and the hydrogen gas passes through the caps *g* and connections *m* into the collecting vessel *I*, which is separate from the dissolving apparatus and is preferably of iron. In this vessel *I* the hydrogen gas collects in the gas-chamber *n*, while the fluid freed from gas flows into the chamber *o*. The chamber *o* is at the upper end of the discharge-pipe *q* provided with a gas-separator *p*, formed in such a way that the level of the fluid in the same is approximately equal to that of the anode electrolytes in the dissolving-chamber—that is to say, with the level of the discharge-pipes *l*. The mixture of alkali hydrate and alkali-salt solution flows out through the discharge-pipe *q* and the closing-tap *r*, or in order to pass directly into the apparatus for separating its content of salts the hydrogen gas is carried off from the gas-chamber through the aperture *s* and utilized in any suitable way. When the ore is extracted to the desired extent, the anode fluid is let off from the pan through the pipes *k* and the cathode fluid through the pipes *f*, after which the gases are drawn off, whereupon the residues from the extraction-chamber may be washed out through the nozzles *L*. The residues are in the ordinary way conveyed to the tip.

Having thus described one embodiment of my invention, what I claim, and desire to secure by Letters Patent, is—

60 1. An apparatus for extracting metals from ores and other metalliferous substances, consisting of an upper chamber to receive the ore to be treated, a lower chamber, a permeable false bottom between the upper and lower chamber, electrodes of both poles ar-

ranged in said lower chamber, diaphragms surrounding the cathodes, means for connecting the cathodes and anodes to the poles of a source of electrical energy, and means to feed into and to discharge the cathode electrolyte from the diaphragms. 7c

2. An apparatus for extracting metals from ores and other metalliferous substances, consisting of an upper chamber to receive the ore to be treated, a lower chamber, a permeable false bottom between the upper and lower chamber, electrodes of both poles arranged in said lower chamber, diaphragms surrounding the cathodes, means for connecting the cathodes and anodes to the poles of a source of electrical energy, means to feed into and to discharge the cathode electrolyte from the diaphragms, and means to feed the anode electrolyte into the lower chamber. 75

3. An apparatus for extracting metals from ores and other metalliferous substances, consisting of an upper chamber serving for receiving the ore to be treated, a lower chamber, a permeable false bottom between the upper and lower chamber, electrodes of both poles arranged in said lower chamber, diaphragms surrounding the cathodes, means for connecting said cathodes and anodes to the poles of an electric-current source, means to feed into and to discharge the cathode electrolyte from said diaphragms, means to feed the anode electrolyte into the lower chamber and means to discharge the anodic electrolyte from the upper chamber. 85

4. An apparatus for extracting metals from ores and other metalliferous substances, consisting of an upper chamber serving for receiving the ore to be treated, a lower chamber, a substantially horizontal permeable false bottom between the upper and lower chamber, anodes of insoluble material in the lower chamber, distributed uniformly under the permeable bottom, free spaces between the anodes, inlets for the anode electrolyte under the anodes, cathodes in the lower chamber, distributed uniformly over the anodes and arranged in proximity thereof, diaphragms surrounding the cathodes, there being apertures between said diaphragms uniformly distributed over the anodes, 90 means to feed the cathode electrolyte into the diaphragms, means to discharge it from said diaphragms, and means to withdraw the electrolyte from the top of the upper chamber. 95

5. An apparatus for extracting metals from ores and other metalliferous substances, consisting of an upper chamber serving for receiving the ore to be treated, a lower chamber, a substantially horizontal permeable false bottom between the upper and lower chamber, anodes of insoluble material in the lower chamber distributed uniformly under the permeable bottom, there being apertures on said anode-plates allowing a free passage 100

- to the anode electrolyte, inlets for this latter uniformly distributed under the anode-plates, a plurality of tubular diaphragms in the lower chamber arranged in proximity of the anodes and forming a grate covering the whole area corresponding to the permeable bottom, cathodes extending through said tubular diaphragms, an alkali-collecting vessel, means for connecting one end of said tubular diaphragms with the alkali-collecting vessel, a cathode-electrolyte conduit, and means for connecting the other end of the diaphragm-tubes with the cathode-electrolyte conduit.

6. An apparatus for extracting metals from ores and other metalliferous substances, consisting of an upper chamber serving for receiving the ore to be treated, a lower chamber, a substantially horizontal permeable false bottom between the upper and lower chamber, anodes of insoluble material in the lower chamber distributed uniformly under the permeable bottom provided with apertures allowing the free passage to the anode electrolyte, inlets for this latter uniformly distributed under the anode-plates, a plurality of tubular diaphragms in the lower chamber arranged in the proximity of the anodes and forming an inclined grate covering the whole area corresponding to the permeable bottom and rising from the feed end toward the discharge end, the tubular diaphragms being inserted on the one end separately and connected on the other end in groups by means of feeding-tubes, cathodes extending through said diaphragms, an alkali-collecting vessel, means for connecting one end of said diaphragm-tube with the alkali-collecting vessel, a cathode-electrolyte conduit, and means for connecting the other end of the diaphragm-tubes with the cathode-electrolyte conduit.

8. In an apparatus of the kind described embodying diaphragm-tubes, a head-piece for the diaphragm-tubes provided with a lateral tubular projection, a bolt tightly fitted in said tubular projection, a contact-piece secured to the inner end of said bolt and projecting from the mouth of the head-piece, means for securing the cathode to the projecting end of the contact-piece, an alkali-collecting vessel, means for connecting the one end of the head-piece with a diaphragm-tube and the other end with a connection leading to the alkali-collecting vessel.

In testimony whereof I affix my signature to this specification in the presence of two witnesses.
